STORAGE TRAY FOR MARKING IMPLEMENTS

Thomas F. Furlong, Jr., 206 Norwell St.,
Dorchester, Mass.

Filed Jan. 23, 1962, Ser. No. 68,487

Term of patent 3½ years

(Cl. D58—13)

FIG. 1

FIG. 3

FIG. 1 is a view in perspective of a storage tray for marking implements, showing my new design;

FIG. 2 is a top plan view thereof, the dot-dash line illustration of a marking implement being for illustrative purposes only; and

FIG. 3 is a side elevational view of the showing made in FIG. 1.

The broken line illustration of the cover in FIG. 1 and the marking implement in FIG. 2 are for illustrative purposes only, the dominant features of the design being shown in the full lines.

I claim:

The ornamental design for a storage tray for marking implements, substantially as shown and described.
